METHOD OF AND COMPOSITION FOR INHIBITING FOAMING IN STEAM BOILERS

Lewis O. Gunderson, Park Ridge, Ill., assignor to
Dearborn Chemical Company, Chicago, Ill., a
corporation of Illinois

No Drawing. Application March 19, 1945,
Serial No. 583,647

8 Claims. (Cl. 252—321)

1

One feature of the present invention relates to the incorporation of redwood bark dust or alkali derivatives of redwood bark to boiler water, whereby the sludge in the boiler water is dispersed and/or solubilized and encrustation of boiler surfaces or formation of hard deposits of calcium or magnesium compounds is prevented or lessened.

Another feature of this invention relates to a method and a composition for conditioning water for the prevention of foaming in water, in particular, boiler waters, having a tendency to foam. More especially, the invention pertains to a composition and a method of the nature indicated involving the addition of a composition selected from the group consisting of redwood bark dust, an alkali derivative of redwood bark dust, an alkali derivative of redwood bark, and an alkali derivative of redwood bark fiber, for the purpose of increasing the efficiency and/or the efficient lives of foam inhibiting compositions such as those disclosed in my United States Patents No. 2,328,551 (issued September 7, 1943) and 2,366,727 (issued January 9, 1945) and in my copending applications, Serial Nos. 305,959 (filed November 24, 1939); 458,142 (filed September 12, 1942); 501,293 (filed September 4, 1943); 504,076 (filed September 27, 1943) now abandoned; 560,899 (filed October 28, 1944); 568,202 (filed December 14, 1944); 568,203 (filed December 14, 1944); 568,204 (filed December 14, 1944); 568,205 (filed December 14, 1944); 568,206 (filed December 14, 1944), and 568,207 (filed December 14, 1944).

As disclosed in the above identified applications, foaming of boiler water is not, as commonly thought, equivalent to an accumulation of foam on top of the surface of the boiler water. When steam is rapidly withdrawn from a boiler with resultant foaming, there is no water surface within the boiler correlated with the water level indicated in the conventional waterglass attached to the boiler. In other words, there is no sharp line of demarcation between solid water and foam in the boiler during rapid steam withdrawal.

The foaming of boiler water is actually a rapid expansion of the water in the steam generating area of the boiler brought about by the fact that rapidly forming small steam bubbles do not coalesce until a definite short time after their formation. As a consequence, the entire volume of water in the generating area is expanded by myriads of bubbles until the thus formed so-called "light water" fills the steam space and

becomes entrained with the steam leaving the boiler.

In other words, bubbles need not be particularly stable to cause boiler foaming. The stability of the bubbles need only be such that the bubbles last but a very few seconds after passing the plane of the water level indicated in the waterglass.

As disclosed and claimed in my above identified patents and applications, I have invented methods for conditioning water for steam generation by incorporating with said water from a trace to twenty-five or fifty parts per million or more of a surface-active predominantly hydrophobic organic substance comprising molecules each including a group of closely spaced interconnected hydrophilic radicals and a plurality of long unsubstituted hydrocarbon chains attached to said group (Patent No. 2,328,551); or of surface-active predominantly hydrophobic organic substances represented by the formula

in which R represents a hydrocarbon chain containing at least ten carbon atoms, R₁ represents at least one hydrocarbon chain containing at least ten carbon atoms and X represents a radical selected from the group consisting of the N, NH, NCO and NHCO radicals; or of predominantly hydrophobic surface-active organic substances comprising a plurality of spaced hydrophilic nitrogen containing radicals interconnected by carbon atoms and having a plurality of hydrocarbon chains containing each at least eight carbon atoms attached severally to said nitrogen containing radicals (application, Serial No. 305,959, now U. S. Patent No. 2,442,768, issued June 8, 1948); or of polyalkylene polyamines having both primary amino groups and at least one secondary amino group acylated with a higher fatty acid (application, Serial No. 458,142, now U. S. Patent No. 2,461,730, issued February 15, 1949); or of polyalkylene polyamines having two primary groups acylated with a higher fatty acid (application, Serial No. 501,293); or of a product having a molecular weight of at least one thousand derived by condensation of a polymerized higher fatty acid compound with a compound selected from the group consisting of the alkylene diamines, the polyalkylene polyamines, the alkanol amines, the alkanol alkylene diamines, the alkanol polyalkylene polyamines, and the condensation products of two moles of a dibasic aliphatic amine with one mole of a dibasic carboxylic acid (application, Serial No. 560,899, now U. S. Patent

No. 2,493,453, issued January 3, 1950); or of a compound having the formula

in which Y represents a radical selected from the group consisting of the SO_3 and SO_4 radicals, R represents a hydrocarbon chain containing at least ten carbon atoms and R_1 represents a hydrocarbon chain containing at least ten carbon atoms (application, Serial No. 568,202); or of a predominantly hydrophobic quaternary ammonium compound having the formula

in which R represents a hydrocarbon chain containing at least twelve carbon atoms, R_1 represents a hydrocarbon chain containing at least twelve carbon atoms, R_2 represents a hydrocarbon chain containing at least twelve carbon atoms, and R_3 represents a hydrocarbon chain containing from one to eleven carbon atoms and Hal represents a halogen atom (application, Serial No. 568,203); or of a secondary aliphatic amine having the general formula

in which R and R_1 represent hydrocarbon chains each containing at least ten carbon atoms, at least one of said hydrocarbon chains being straight (application, Serial No. 568,204 now abandoned); or of a tertiary aliphatic amine having the general formula

in which R represents a hydrocarbon chain containing at least ten carbon atoms, R_1 represents another hydrocarbon chain containing at least ten carbon atoms, and R_2 represents a hydrocarbon chain, at least one of the hydrocarbon chains R and R_1 being straight (application, Serial No. 568,205 now abandoned); or of a compound having the general formula

in which R represents a hydrocarbon chain containing at least twelve carbon atoms, R_1 represents a hydrocarbon chain, and R_2 represents a hydrocarbon chain containing at least eight carbon atoms, at least one of the hydrocarbon chains R and R_2 being straight (application, Serial No. 568,206); or of a compound having the general formula

in which R represents a hydrocarbon chain containing at least twelve carbon atoms, and R_1 represents a hydrocarbon chain containing at least twelve carbon atoms, at least one of said two hydrocarbon chains being straight (application, Serial No. 568,207); or of other and further compounds disclosed or claimed in any one of the above identified applications and patents.

I have further disclosed in said patents and applications that the above indicated foam inhibiting compositions may be introduced into steam boiler water in the form of colloidal dispersions that may be stabilized with tannin, gum arabic or pectin. If desired, the foam inhibiting compositions may be introduced into the boiler in the form of a solution in an appropriate solvent, such as isopropyl alcohol. The dosages required are generally quite small, on the order of

some few parts per million of boiler water. In general, from a trace to about twenty-five or about fifty parts per million of foam inhibiting compounds may be added to boiler water, preferably in combination with tannin. Additional foam inhibiting compounds may be repeated as required to prevent foaming.

A preferred method of adding the foam inhibiting compounds to boiler feed water comprises the incorporation of the effective foam inhibiting ingredients in a powdered formula, the constituents of which cooperate in greater or less degree in increasing the efficiency of the foam inhibiting effect. Such formulae may be added manually directly to the locomotive tender, or the powder may be dissolved in water in mixing vats and subsequently pumped into feed water storage tanks in specific proportions with the feed water to obtain uniform treatment of the water. The following are examples of such powdered formulae:

	Per cent
1. A reaction product of ethylene diamine and 12-palmitate-9-octadecenoic acid, in a mole ratio of 1:4	2
25 Tannin (chestnut oak)	40
Tannin (quebracho)	4
Soda ash	53
Sodium hexametaphosphate	0.5
Chrome alum	0.5
30 2. Dioleyl amide of ethylene diamine	1.5
Tannin	45
Lanthanum chloride	0.5
Tartaric acid	0.5
Soda ash	52.5
35 3. Reaction products of ethanol triethylene tetramine and the fatty glycerides, such as soy bean oil, in a mole ratio 1:5	2.5
Tannin	45
40 Manganese glutamate	0.5
Saccharic acid	0.5
Soda ash	51.5
45 4. Condensation products (1:1 mole) of tetra-ethylene pentamine and peanut oil further condensed (1:1 mole) with oleic acid	5
Soda ash	51
Tannin (quebracho)	4
Tannin (chestnut)	40

It will be noted that the above disclosed compositions include tannin. The amount of tannin used may vary from about 5 to about 100 times of the amount of the particular organic foam inhibiting compounds employed, and serves to render these organic foam inhibiting compounds more efficient and to prolong their effective lives.

I have now found that in place of the tannin, gum arabic, pectin or like agents heretofore used in combination with my novel foam inhibiting organic compounds or conventional foam inhibiting compositions such as castor oil, I may use, with equally good results, compositions selected from the group consisting of redwood bark dust, alkali derivatives of redwood bark dust, alkali derivatives of redwood bark, and alkali derivatives of redwood bark fiber.

It is therefore an important object of the present invention to provide methods and compositions for treating boiler water involving the use of redwood bark dust or alkali derivatives of redwood bark.

Other and further objects and features of this invention will become apparent from the following description and appended claims.

The nature and composition of the above mentioned redwood bark compositions are disclosed in an article entitled "Chemical Composition of Redwood Bark" by H. F. Lewis et al. published in the August, 1944, issue of "Industrial and Engineering Chemistry," volume 36, pages 762 to 764. As disclosed in said article, large amounts of redwood bark waste normally result from lumbering operations in the western States. The bark of the redwood tree (at least that part brought in from the woods for conversion into lumber) is a dense, somewhat fibrous material ranging in thickness from an inch or less up to ten inches or more. When the bark is run between milling rolls, the materials forming and lining the cell wall structures disintegrate to form an amorphous powder, commonly referred to as "bark dust" or "bark sand," which can be separated from the fibrous materials contained in the bark. For instance, the bark slabs from the peeling plant can be run through milling rolls to loosen the bark structure, with the subsequent formation of large matted fibrous bundles. This heterogeneous product is then subjected to textile cleaning and carding operations. A large percentage of the fiber is obtained as a loose fill insulation in fairly clean fiber bundles possibly one to two inches long. These bundles still retain some of the original bark structure and composition. The remainder of the fibers is separated from the bark dust as cleaned textile fiber approximately one-quarter to three-quarters inch in length, with the fiber bundles well separated into what appear to be isolated fibers. Each filament, however, consists of several ultimate bark fibers intertwined into a characteristic corkscrew structure. The greater share of the bark dust is taken from the condensers during the textile operation and at the present time is burned for lack of a better use. At least half of the weight of the bark is lost as dust in this stage of the operation.

The bark dust obtained as described above or by other methods may be used as obtained for the purpose of my present invention by incorporation with boiler water in amounts ranging from about five to one hundred times the amount of the organic foam inhibitor employed. This dust is made up of broken fibers, small cells, and the powdered walls of dead parenchyma cells and sieve cells, together with the dried contents of these and the cork cells. If desired, the bark dust may be extracted with alcohol, which removes 1.5% of the dust, including the tannin content thereof. Such alcohol extraction leaves a solid residue which I have found very suitable for the purposes of the present invention.

The bark dust may also be prepared for use in combination with organic foam inhibitors for water conditioning by treatment with solutions of sodium hydroxide or like alkalies. For instance, one part by weight of bark dust may be digested with 3.5 parts by weight of a solution containing 0.3 part by weight of sodium hydroxide at a temperature of approximately 150° C. for a few hours, or until about 88% of the bark dust becomes soluble or colloidally dispersible in water. The digested bark dust, after an optional removal of insoluble matters, such as fibers, by filtration or otherwise, is subjected to an evaporation process to remove the water, and the residue is then ground for admixture to a powdered formula in a manner similar to tannin, or, the dried digested bark dust may also be added sepa-

rately to the boiler feed water, either alone or in conjunction with basic water softening chemicals such as soda ash or caustic soda. Further, such a sodium redwood bark dust may be admixed with various percentages of tannin, to better inhibit encrustation of calcium salts in feed water heaters and feed water pumps or the like.

If desired, such preparation of the sodium derivative of redwood bark dust may be preceded by an extraction of the redwood bark dust with alcohol.

Materials useful according to the present invention may also be prepared by similar digestions with sodium hydroxide, potassium hydroxide, soda ash or the like of the redwood bark fiber, or of disintegrated redwood bark. The concentration of sodium hydroxide may vary from one to twenty percent, or more, and the temperature of digestion may suitably be from 100° to 180° C. The time of digestion may vary from one to five hours, or sufficient time to render from about thirty-five to about eighty-eight percent of the digested material water-soluble or water-dispersible. Extraction with alcohol may precede such digestion.

In general, the sodium derivatives of redwood bark, redwood bark dust and redwood bark fiber may be prepared by any suitable method of digestion with aqueous sodium hydroxide or the like at temperatures above 100° C. continued until a substantial portion of the material has been rendered water-dispersible or water-soluble, the digestion, if desired, being carried out under super-atmospheric pressure. On a large scale, I prefer to use a jacketed digester where the heat is produced by steam pressure. A rotary digester is very satisfactory for this purpose since it can be discharged easily. At the end of a digestion period, the entire digester charge is dried in some convenient drying system, and the dried product is ground.

As indicated in the above identified article, the sodium salt formed by the digestion treatment disclosed appears to be a derivative of a lignin-like material easily soluble in dilute alkaline solutions and containing little if any methoxyl, but significant percentages of free carboxyl and phenolic hydroxyl groups. Apparently redwood bark and its constituent parts (redwood bark dust and redwood bark fiber) contain large quantities of high molecular weight phenolic acids related to lignin and resembling humic acid in many ways. This acidic material, I believe, may be one of the active constituents of redwood bark for the purposes of the present invention, either as dissolved out or hydrolyzed out of redwood bark dust when added to boiler water (which as a rule is alkaline) or after digestion with alkali.

Very successful results have been obtained by adding redwood bark dust, the sodium derivative of redwood bark dust, the sodium derivative of redwood bark fiber, or the sodium derivative of redwood bark, in finely ground condition, to boiler water, for instance, in the ratio of one pound of redwood bark dust or other material to about 2,500 to 25,000 gallons of boiler water, in conjunction with a simultaneous use of from a trace to fifty parts per million of an alkylene diamine or alkylene polyamine acylated with a higher fatty acid. More particularly, I may use an ethylene diamine or a polyethylene polyamine acylated with a fatty acid containing at least twelve and preferably at least sixteen carbon atoms, such as oleic acid, stearic acid, lauric acid,

palmitic acid, ricinoleic acid, and the like. In the case of ethylene diamine, both amino groups should be acylated. In the case of polyalkylene polyamines, both primary amino groups should preferably be acylated, and one or more of the secondary amino groups may also be acylated. Specific examples of ethylene diamines and di-amides include dioleyl ethylene diamine, di-stearoyl ethylene diamine, dipalmityl ethylene diamide, and diricinoleyl ethylene diamide. Examples of derivatives of polyalkylene polyamine are the oleyl, stearoyl, palmityl, ricinoleyl, and linoleyl di- or tri-derivatives of diethylene tri-amine, triethylene tetra-amine, tetra-ethylene pentamine, and the like. The corresponding derivatives of lauric acid may also be employed. More than one higher fatty acid may be employed in the preparation of any one of these polyalkylene polyamine and alkylene diamine derivatives.

Very good results have been obtained by the concurrent addition to alkaline locomotive boiler water of the above disclosed redwood bark dust or redwood bark alkali derivatives and the di-amide of ethylene diamine with the fatty acids of soy bean oil or polymerized fatty acids of soy bean oil (as disclosed in my application, Serial No. 560,899). These and other polyamides of aliphatic amines with higher acids may, if desired, be incorporated with redwood bark dust or alkali derivatives of redwood bark by being sprayed, in liquid condition, onto redwood bark dust or alkali derivatives of redwood bark, preferably followed by heating at approximately 100° C. for a short time to favor absorption of polyamide by the sodium bark dust.

When redwood bark dust, or alkali derivatives of redwood bark, are used per se for the purpose of lessening or preventing encrustation or scale formation due to deposition of insoluble calcium or magnesium compounds, the redwood bark dust or the alkali redwood bark derivatives, may be added in amounts varying from one pound per 2,500 gallons of boiler water to one pound per 25,000 gallons of boiler water. At these concentrations, the calcium or magnesium compounds will be inhibited in their normal tendency to deposit on physical surfaces, such as on surfaces of metals comprising feed water pumps, injectors, pipes, etc.

The methods and compositions of this application are particularly applicable to the treatment of water used in the generation of high pressure steam, for instance, in locomotives, where the generated steam pressure may exceed one hundred or two hundred pounds per square inch.

Many details of procedure and composition may be varied within a wide range without departing from the principles of this invention and it is, therefore, not my purpose to limit the patent granted on this invention otherwise than necessitated by the scope of the appended claims.

I claim as my invention:

1. The method of generating steam from a boiler water having a tendency to foam on boiling which comprises dispersing into said water ethylene diamine diacylated with a fatty acid containing at least twelve carbon atoms in an effective amount up to 50 parts per million of boiler water, together with a substance selected from the group consisting of redwood bark dust, a water dispersible alkali derivative of redwood bark dust, a water dispersible alkali derivative of redwood bark fiber, and a water dispersible alkali derivative of redwood bark, in an amount equivalent to

a ratio of one pound of the redwood bark material for every 2500 to 25,000 gallons of boiler water, and heating the resulting aqueous dispersion to the boiling point, the substances dispersed into said water functioning to inhibit the tendency of said water to foam on boiling.

2. The method of generating steam from a boiler water having a tendency to foam on boiling which comprises dispersing into said water a polyethylene polyamine acylated with at least two moles of a fatty acid containing at least twelve carbon atoms for each mole of said polyethylene polyamine in an effective amount up to 50 parts per million of boiler water, together with a substance selected from the group consisting of redwood bark dust, a water dispersible alkali derivative of redwood bark dust, a water dispersible alkali derivative of redwood bark fiber, and a water dispersible alkali derivative of redwood bark, in an amount equivalent to a ratio of one pound of the redwood bark material for every 2500 to 25,000 gallons of boiler water, and heating the resulting aqueous dispersion to the boiling point, the substances dispersed into said water functioning to inhibit the tendency of said water to foam on boiling.

3. The method of generating steam from a boiler water having a tendency to foam on boiling which comprises dispersing into said water a polyethylene polyamine diacylated with a fatty acid containing at least twelve carbon atoms in an effective amount up to 50 parts per million of boiler water, together with a substance selected from the group consisting of redwood bark dust, a water dispersible alkali derivative of redwood bark dust, a water dispersible alkali derivative of redwood bark fiber, and a water dispersible alkali derivative of redwood bark in an amount equivalent to a ratio of one pound of the redwood bark material for every 2500 to 25,000 gallons of boiler water, and heating the resulting aqueous dispersion to the boiling point, the substances dispersed into said water functioning to inhibit the tendency of said water to foam on boiling.

4. The method of generating steam from a boiler water having a tendency to foam on boiling which comprises dispersing into said water a polyethylene polyamine whose primary amino groups are acylated with a fatty acid containing at least sixteen carbon atoms in an effective amount up to 50 parts per million of boiler water, together with a substance selected from the group consisting of redwood bark dust, a water dispersible sodium derivative of redwood bark dust, a water dispersible sodium derivative of redwood bark fiber, and a water dispersible sodium derivative of redwood bark, in an amount equivalent to a ratio of one pound of the redwood bark material for every 2500 to 25,000 gallons of boiler water and heating the resulting aqueous dispersion to the boiling point, the substances dispersed into said water functioning to inhibit the tendency of said water to foam on boiling.

5. The method of generating steam from a boiler water having a tendency to foam on boiling which comprises dispersing into said water ethylene diamine whose primary amino groups are acylated with a fatty acid containing at least sixteen carbon atoms in an effective amount up to 50 parts per million of boiler water, together with a substance selected from the group consisting of redwood bark dust, a water dispersible sodium derivative of redwood bark dust, a water dispersible sodium derivative of redwood bark

fiber, and a water dispersible sodium derivative of redwood bark, in an amount equivalent to a ratio of one pound of the redwood bark material for every 2500 to 25,000 gallons of boiler water and heating the resulting aqueous dispersion to the boiling point, the substances dispersed into said water functioning to inhibit the tendency of said water to foam on boiling.

6. A composition adapted to be dispersed into a boiler water having a tendency to foam on boiling and, when so dispersed, functioning to inhibit said foaming tendency, said composition comprising ethylene diamine acylated with at least two moles of a fatty acid containing at least twelve carbon atoms in an effective amount up to 50 parts per million of boiler water and a substance selected from the group consisting of redwood bark dust, a water dispersible alkali derivative of redwood bark dust, a water dispersible alkali derivative of redwood bark fiber, and a water dispersible alkali derivative of redwood bark, in an amount equivalent to a ratio of one pound of the redwood bark material for every 2500 to 25,000 gallons of boiler water.

7. A composition adapted to be dispersed into a boiler water having a tendency to foam on boiling and, when so dispersed, functioning to inhibit said foaming tendency, said composition comprising a polyethylene polyamine acylated with at least two moles of a fatty acid containing at least twelve carbon atoms for each mole of polyalkylene polyamine in an effective amount up to 50 parts per million of boiler water, and a substance selected from a group consisting of redwood bark dust, a water dispersible alkali derivative of redwood bark dust, a water dispersible alkali derivative of redwood bark fiber, and a water dispersible alkali derivative of redwood

bark, in an amount equivalent to a ratio of one pound of the redwood bark material for every 2500 to 25,000 gallons of boiler water.

8. A composition adapted to be dispersed into a boiler water having a tendency to foam on boiling and, when so dispersed, functioning to inhibit said foaming tendency, said composition comprising a polyethylene polyamine acylated with at least two moles of a fatty acid containing at least sixteen carbon atoms for each mole of said polyalkylene polyamine in an effective amount up to 50 parts per million of boiler water and a substance selected from the group consisting of redwood bark dust, a water dispersible alkali derivative of redwood bark dust, a water dispersible alkali derivative of redwood bark, in an amount equivalent to a ratio of one pound of the redwood bark material for every 2500 to 25,000 gallons of boiler water.
